UNITED STATES PATENT OFFICE

MAX RÜPING, OF MUNICH, GERMANY

DEVICE FOR STRESSING SPRINGS

Application filed March 3, 1932. Serial No. 596,611.

This invention relates to a device for stressing springs employed for fixing railway rails on their support. Rail fixing means of this kind are described for instance in U. S. A. 5 Patent 1,798,357.

According to the invention the device consists of an inverted U-shaped pressure applying member, the distance between the limbs of which corresponds to the thickness of the rail head and on the top surface of which a cylindrical shaft which is adapted to be turned by a lever is journaled parallel to the rail. At both its ends the shaft is provided with eccentrically disposed journals, each 10 of which serves as a pivot for a gripper tongs arrangement mounted thereon, the gripping arms of which are provided with inwardly directed claws. The length of the gripping arms and of the pressure applying member 15 are suitably made such that, on the pressure applying member being placed on the springs lying on the rail foot, the two gripper tongs engage with their claws under the rail head. Furthermore, each two gripper arms with 20 equally directed claws are connected together 25 above the journal casing by a common handle.

In the accompanying drawing a constructional example of the invention is illustrated.

Fig. 1 is a vertical section through the tool 30 in position on the rail and

Fig. 2 a side elevation corresponding to Fig. 1 without the sheet metal cover.

On the crown of an inverted U-shaped iron *a* is disposed a pressure bearing *b* in which 35 rests a cylindrical shaft *d*. This shaft is provided at either end with eccentrically disposed journals *e*, *e'* each of which is journaled in the pivot holes at the end of each of the two grippers *f*. In the example shown, 40 these grippers *f* engage with those claws *f'* under the head of the rail *g*, when the inverted U-shaped iron *a* is placed over the rail *g*. The ends of the limbs *a'* of the inverted U-shaped iron bear against the springs *h*. Of 45 the two journals *e* and *e'* the journal *e'* is somewhat extended and is made hexagonal at its end for slipping on a spanner *i*. Through turning the shaft *d* by means of the spanner *i* the pressure bearing *b* is pressed 50 against the inverted U-shaped iron *a* and con-

sequently the ends of the limbs *a'* of the inverted U-shaped iron against the springs *h*, so that these springs are stretched, that is stressed. The gripper claws *f'* bear from 55 below against the rail head.

The inverted U-shaped iron is so formed at its limb ends that above the springs it leaves room for the heads of the two spring clips *l*. When these spring slips have been 60 pushed under the bow *m*, the tension applying apparatus is released by turning back the shaft *d* and is then removed. The springs are thus clamped under the spring clips *l*.

The eccentric gear is surrounded by a protection sheet *n*. The object of the latter is 65 not only to keep away dirt but also to prevent the eccentric gear from being lifted off the inverted U-shaped iron *a* when the appliance is being carried.

Of the four grippers *f* each two on the same 70 side of the rail are connected together by a common handle *o*. By pressing the two handles *o* together the tongs formed by the grippers are opened and on the handles being released the tongs close again so that the attachment and removal of the tensioning apparatus into and out of its operative position 75 is extremely convenient and simple. This is of particular importance for carrying out 80 repairs when the line is in use. The apparatus enables both springs to be tensioned at the same time through applying pressure by a lever. The springs are held in the tensioned state automatically as the frictional action 85 of the eccentric prevents the latter turning back unintentionally. Consequently the man who tensions the springs can also apply the spring clips *l*.

The limbs *a'* of the inverted U-shaped iron 90 are provided at their lower ends with openings *p*. These openings are of such a shape that between their upper edge and the end of the spring clip *l* a crow-bar like lever *q* can be inserted. By swinging the upper end of 95 this lever upwards the spring clip can be forced out when it cannot be removed by hand only for the purpose of releasing the rail fastening.

What I claim is:—
1. A device for stressing springs used for 100

fixing railway rails to their supports, comprising in combination an inverted U-shaped member having its limbs spaced apart by the thickness of the rail head, a cylindrical shaft 5 on the crown of the said inverted U-shaped member capable of being rotated and lying parallel to the rail, a bearing for said shaft, the bearing being disposed on the crown of the said inverted U-shaped member and capable 10 to slide transversely to the rail, eccentrically arranged journals at the ends of the shaft, two pairs of gripper tongs pivoted at the journals, inwardly directed claws at the ends of the arms of said tongs and the length 15 of the said gripper arms being in such proportion to the height of the inverted U-shaped pressure member, that on the said member resting on the two springs lying on the foot of the rail the said claws will be in a position 20 to engage under the head of the rail.

2. A device according to claim 1 two handles arranged above the bearing each connecting the two arms of that gripper tongs having similarly directed claws.

25. In testimony whereof I affix my signature.
MAX RÜPING.
